BIRD CAGE

Adolph J. Havlis, Chicago, Ill., assignor to Earl
W. Little, Indianapolis, Ind.

Application September 6, 1938, Serial No. 228,550

13 Claims. (Cl. 119—17)

This invention relates to bird cages and more particularly to round cages incorporating the use of a drawer or tray in the base of the cage and removable for cleansing purposes.

5 The conventional type of cage base has a slot therein for receiving the drawer and the formation of the slot in the base reduces the strength of that portion of the base directly below the slot, thus weakening the band at this point to 10 such an extent as to permit the same to easily sag or bend. Heretofore, if the size of the cage was increased it became necessary to increase the width of the tray to retain the sides of the tray beneath the overhang of the cage, consequently it was necessary to lengthen the slot in 15 the cage base to accommodate the enlarged tray. With the lengthening of the slot in the base, that portion of the base below the slot becomes increasingly weaker. Thus the sizes of 20 cages heretofore have been restricted in size to the length the slot could be made without causing the base portion below the slot to sag.

In constructing the cage base and tray as disclosed in the present invention the length of the 25 slot in the base for accommodating the drawer or tray is substantially less than the confines of the overhang or the inside diameter of the cage so that a much larger cage can be constructed without increasing the length of the slot or the 30 width of the tray and false bottom associated therewith, to correspond with the increased diameter of the overhang as heretofore.

One feature of the invention is the provision of a removable tray or drawer and a false bottom, 35 both of which have sliding engagement with removable guiding and supporting means located in the cage base, thereby dispensing with the conventional form of fasteners formerly employed for securing the base portion to the body 40 portion of the cage structure and providing a stronger and more solidified structure and one that may be more cheaply manufactured and more readily nested together for shipping purposes.

45 A further feature of the invention is in so constructing the removable tray and false bottom that the diameter of the cage structure can be much greater than the width of the tray and false bottom, thus greatly reducing the amount 50 of material heretofore used in the manufacture of these parts.

A further feature of the invention is in positioning the false bottom below the tray and in the supporting elements therefor so that when 55 the tray is removed the false bottom may re-

main within the cage and form a closure therefor and prevent the bird escaping, the tray being removable from above said false bottom without removing the cage from its hanger or support.

Another feature of the invention is in so constructing the tray and bottom forming member that the wire cage body may be made much larger than the width of the tray and false bottom, thus giving a much greater flight space within the cage. 5

A further feature of the invention is the provision of a pair of removable shields to replace the overhang of the cage for preventing waste matter or droppings being deposited in the space between the sides of the tray and walls of the 15 cage, the shields having means for supporting the tray and false bottom and for guiding them into proper position in the cage base and for holding said drawer and false bottom against vertical movement when positioned within the 20 cage.

A further feature of the invention is in so constructing and mounting the shields and tray that when in operative position they will reinforce the walls of the cage base. 25

A further feature of the invention is in so constructing the removable shields that the length of the slot through which the tray and false bottom enter the cage base will be materially reduced with respect to the inside diameter of the 30 cage body, thus preventing sagging of that portion of the base directly below the slot.

A further feature of the invention is the provision of means for removably attaching the combined shield and guide units to the inner 35 face of the cage base so that they may be removed when a plurality of cage structures are to be nested together for shipping purposes, portions of said shields being constructed for interlocking with parts of the cage base for rigidly 40 holding the shields against movement in any direction when attached to the base portion.

A further feature of the invention is in constructing the cage base with a slot of much less length than the width of the diameter of the 45 cage through which the tray and false bottom may be entered or removed, combining therewith shields having combined guides and supports for aligning the tray and false bottom when entered through said slot, the position of said shields permitting free access to the interior of the cage, when the tray and false bottom are removed from the cage. 50

A further feature of the invention is in disposing the edges of the shields contacting the inner 55

face of the base portion beneath the overhang so that no droppings or the like will pass between the wall of the base and the contacting edges of the shields.

- 5 A further feature of the invention is in so positioning the shields that the outer ends thereof will register with the end walls of the slot and with the lower sections of the supporting elements slightly below the bottom edge of the slot 10 so that the top face of the false bottom will rest substantially level with the lower edge of the slot and be held stationary when the tray is being removed.

A further feature of the invention is to provide 15 a cage of simple and inexpensive construction, that may be made, finished, packed and shipped more expeditiously and at less cost than the cages as heretofore constructed and in which the increased diameter of the cage may be compensated for by increasing the size of the shields without increasing the width of the trays or 20 false bottoms.

Further objects and advantages of the invention will be apparent from the detailed description taken in connection with the accompanying drawings, in which:

Figure 1 is an elevational view of a cage embodying the invention.

Figure 2 is an enlarged sectional view thereof 30 as seen from line 2—2, Fig. 1.

Figure 3 is an enlarged sectional view as seen from line 3—3, Fig. 2.

Figure 4 is a similar view, taken at right angles to Fig. 3, as seen from line 4—4, Fig. 2.

35 Figure 5 is an isometrical perspective view of the tray supporting element removed from the cage.

Figure 6 is a top plan view of the tray or drawer.

40 Figure 7 is a top plan view of the false bottom for the cage.

Figure 8 is a front elevational view of the drawer structure, parts being shown by dotted lines.

45 Figure 9 is an edge view of the false bottom.

Figure 10 is a transverse sectional view through the base portion of a cage showing a cage of smaller diameter, and.

50 Figure 11 is a similar view showing a cage of increased diameter without increasing the width of the tray.

Referring to the drawings in which similar reference numerals designate corresponding parts throughout the several views the numeral 1 designates the upper or body portion of a cage which is preferably circular in formation and formed of the conventional wires 2, the lower ends of which are secured in any suitable manner to the band portion 3 of a base forming member 4, thus 55 uniting the body and base forming members into a single concrete unit. The body portion 1 of the cage is preferably tapered so that the body portion of one cage may pass a substantial distance through the base member 4 of a succeeding cage 60 whereby a plurality of cages may be nested together for shipping, storage or other purposes.

The member 4 is in the nature of a frame and immediately below the band 3 is an outwardly bowed portion forming an enlarged rib 5, terminating at its lower extremity in an inwardly bowed rib 6, the lower edge of the rib 6 in turn terminating in a vertically extending frame section 7, in the lower portion of which are formed a pair of reinforcing ribs 8 and 9, the rib 9 being 75 at the lower edge of the frame section 7 and

forming a supporting rest for the cage structure.

The diameter of the band 3 is less than the diameter of the member 4, as is common in cages of the present construction so that any droppings from the body of the cage will descend in a receptacle provided for catching them, but the size of such receptacles must be regulated to the diameter of the cage to prevent the droppings missing the receptacle and passing between the edges of the receptacle and the walls of the cage base, 5 thus limiting the size to which the cages may be successfully made.

It is one of the essential features of the present invention to so construct the tray 10 as to render the same substantially oblong and of much 15 less width than the inner diameter of the cage body, the side edges 11 of the tray extending in straight parallel lines a prescribed distance while the ends 12 are curved substantially to the same curvature as that of the member 4, so that said 20 ends will extend beneath the overhang formed at the upper end of the member 4.

This manner of constructing the tray 10 positions the side flanges 13 of the tray, which traverse the side edges 11, a distance inside the field 25 of the overhanging portion 14, common to cages of this nature, and to prevent droppings and the like passing to the outside of the tray and being thus deposited in the space between the side edges of the tray and the member 4, a pair of 30 shields 15 are provided, the wing portions 16 thereof being inclined downwardly with the extreme upper edge 17 thereof curved to fit the curvature of the under face of the rib 5 and extending beneath the overhang 14, while the ends 35 of wings 16 also extend beneath the overhang 14 and are provided with notches 18 which interlock with the inwardly bowed ribs 6 for holding the shields against pivotal or swinging movement when the shields are attached to the collar member 4. By placing the top edges 17 and ends of the wing portions 16 beneath the overhang 14, droppings are prevented from contacting the shields at these points.

The lower edge of each shield 15 is bent to 45 form a channel 19 in which the tray 10 rests when entered into the cage, the lower extremity of the wing 16 being preferably provided with a lip 20, which slightly overhangs the side flanges 13, while the lower extremity of the channel 19 50 has a shelf portion 21 on which the tray is adapted to rest.

The shields 15 are attached to the member 4 in any suitable manner, in this instance by extending a bolt 22 from each shield to and through 55 a bore 23 in the member 4 and threading a nut 24 onto each bolt and clamping the top edge 17 of each shield firmly against the inner face of the enlarged rib 5 and of the notches 18 in engagement with the rib 6, it being understood that 60 any other suitable fastening means may be used.

The tray or drawer 10 is entered into the cage through a slot 25 formed through the wall of the member 4 and by reducing the width of the tray, the length of the slot 25 may be shortened to such 65 an extent that the sagging of the parts of the member 4 below the slot 25, common to cages of the conventional type, will be practically eliminated and by forming the body and base portions of the cage in an integral unit and sliding the 70 tray into the cage in the manner shown, the cage structure will be far stronger and the production cost thereof greatly reduced. Likewise, by making the two sections of the cage into a single unit, the conventional form of hooks, formerly used 75

for securing the bottom section to the upper portion of the cage, are dispensed with and the unsightly sagging bottom portion is eliminated and a cage is produced that can be packed for shipment as a whole and not in two or more sections as is now required with the two piece cage structures.

Due to the curvature of the member 4, the ends 26 of the shelf portions 21 are curved to fit the inner circumference of the member 4 so that the tray 10 will freely enter the slot 25, the shelf portions 21 being positioned slightly below the top edge of the slot 25. By properly positioning the bores 23 through the walls of the member 4, the ends of the shields 15 will always position or register with the ends of the slot 25 and the channels 19 be positioned to receive the tray 10, when entered through the slot 25, the bolts 22 and bores 23 forming perfect guides for positioning the shields, regardless of the size of the cage and shields. Furthermore, the rib 6 and notches 18 will, when interlocked, prevent undue tilting of the shield and hold the shield in substantially horizontal alinement with the slot 25.

25 By extending the shields upwardly from the tray 10 and thence outwardly over the space between the edge of the tray and member 4, a pocket will be formed, through which will extend the means for attaching the shield to the member 4.

It will likewise be seen that the shields may be removed or attached at will without dismantling or removing other parts of the cage structure as the shields are units in themselves and by increasing or decreasing the dimensions of the shields, they may be attached to cages of different diameters without increasing or decreasing the length of the slot 25.

In addition to the tray 10, a false bottom 27 is provided, which is designed to pass beneath the tray and rest directly on the shelf portions 21 and by positioning the member 21 slightly below the lower edge of the slot 25 or to such a degree that the top face of the false bottom 27 will be in line 45 with the bottom edge of the slot 25 the tray may be readily removed without disturbing the false bottom, the wall of the member 4 adjacent the lower edge of the slot holding the false bottom against removal with the tray. The false bottom 27 is in the nature of a flat plate and having the general outlines of the tray 10, that is to say, having its ends curved coincident to the curvature of the member 4 with its side edges 28 extending in parallel straight lines in the same 55 planes as the side edges 11.

This false bottom 27 is designed primarily to form a closure for the lower end of the cage when the tray 10 is removed for cleansing or other purposes and as the false bottom remains within 60 the cage on the removal of the tray, a bird or other occupant of the cage will be prevented from escaping on the removal of the tray and the cage may be left suspended from its customary support during the removal or return of the tray.

65 By shaping the tray 10 and false bottom 27 in the manner shown, and providing the shields 15, as shown, the diameter of the cage may be increased to any desired size or diameter without increasing the width of the tray and false bottom or the length of the slot through which the tray passes as this structure does not require that the side edges of the tray and false bottom be positioned beneath the overhang 14, as the shields 15 serve the same purpose in this form of cage 70 as the overhangs serve in the cages as formerly 75

constructed. The tray 10 and false bottom 27, together with the shields 15, when properly mounted within the cage base or member 4, will materially brace the member 4 and resist inward strains thereon.

It will likewise be seen that by forming the cage body and base member in a single unit, these elements may be cleansed, painted or enameled at one operation and when enameled, but a single baking oven will be required for baking the enamel on the entire cage at a single operation, thus greatly reducing the expense of production.

It will be further seen that by spacing the shields apart as shown, ready access to the interior of the cage may be had by removing the tray and false bottom from the cage and in order to greatly reduce the cost of shipping, it is but necessary to remove the shields, tray and false bottom, thus leaving the cage structures free to be nested together, such nesting not only reducing the cost of shipping, but materially reinforcing and protecting the parts of the cages against injury.

I claim:

1. The combination with a circular cage body, 25 a circular base portion connected therewith having a slot therein, said body and base portion having a connecting overhang portion, of a tray adapted to be removably entered in said base portion through said slot, said tray having parallel straight side edges and curved end sections, the paralleling side edges resting inwardly of the inner periphery of said cage body and overhang, whereby droppings would pass into the area between the side edges of said tray and the walls of said base portion, means for covering the exposed spaces between said side edges of the tray and the walls of the base portion and for supporting said tray, whereby said slot may be of less length than the inner diameter of said cage 40 body and overhang portion, interlocking means between said space covering means and the wall of said base portion for holding said tray supporting means against undue tilting action and blots attached to said tray supporting means for 45 connecting said supporting means to the inner face of said base, said blots accurately positioning the ends of said tray supporting means in line with the ends of said slot.

2. The combination with a circular bird cage 50 comprising a body and a base portion having a slot therein, an overhang portion at the juncture of said body and base portion, and a tray removably mounted in the base portion of the cage, 55 the width of said tray being less than the inner diameter of said body and overhang portion, whereby droppings from the body portion of the cage in line with the side edges of the tray will drop clear of the tray, of shields made separate 60 from the remainder of the cage and insertable into the cage base after the body and base of the cage proper have been assembled together and having their top and end edges shaped to fit the inner contour of said base portion and having 65 their faces inclined and extending from points beneath said overhang to the side edges of said tray for preventing droppings from descending between the side edges of the tray and the walls of the base portion of the cage, means at the 70 lower extremities of said shields for supporting said tray, means for removably attaching said shields to the inner face wall of said base portion, and means for interlocking said shields with said base portion and substantially aligning them 75

with the ends of the slot in said base portion.

3. The combination with a circular cage structure comprising a body portion and a base portion, said base portion having a slot therein, of a tray adapted to be entered through the slot, said tray having paralleling straight side edges, shields extending from the side edges of said tray to the inner walls of said base portion, means on said shields for supporting said tray, said shields having curved portions adapted to fit the inner curved face of the base, means for interlocking said shields with said base, and means for removably securing said shields to said base portion, said securing means serving to position the ends of said shields adjacent the ends of said slot.

4. The combination with a circular base member of a cage structure having an overhang portion at its upper extremity, said base member having a slot therein, and a tray adapted to enter said base member through said slot, of a pair of shields, bolts for removably connecting said shields with said base member, the top edges of said shields contacting said base member beneath said overhang portion and their ends interlocking with said base member for holding said shields against undue tilting action, and means at the lower extremity of said shields forming supports for said tray, said bolts forming guides for positioning the ends of the shields in alignment with the ends of the slot.

5. The combination with a circular base member of a cage structure having an overhang portion at its upper extremity, said base member having a slot therein, and a tray adapted to enter said base member through said slot, of a pair of shields, means carried by said shields for removably connecting said shields with said base member and forming guides for positioning the ends of the shields in line with the ends of said slot, means at the lower extremities of said shields for supporting said tray, the top edges of said shields contacting said base member beneath said overhang portion, and their ends interlocking with parts of said base.

6. A circular cage structure comprising a body portion and a base portion, said base portion having a slot therethrough, a tray adapted to be entered into said cage through said slot, said tray being of less width than the inner diameter of said base portion, a pair of shields made separate from the remainder of the cage and removably insertable into said base after the body and base portions of the cage have been assembled together, means at the lower extremity of said shields for guiding and supporting said tray, means carried by said shields adapted to contact the wall of said base portion and removably support said shields thereon and align them with the ends of said slot and means for holding said shields against undue tilting action.

7. The combination with a cage body, a base portion connected therewith having a slot therein, an overhang portion carried by said base portion, of a tray adapted to be removably entered into said base portion through said slot, said tray having paralleling straight side edges and curved end sections, said tray being of less width than the diameter of said cage, shields adapted to be removably attached to said base portion and to cover the spaces between the side edges of said tray and the wall of the base of said cage, said shields being insertable into and attachable to the base of the cage after the cage body and base

have been assembled together, integral supporting guides at the lower extremities of said shields for guiding and supporting said tray, connecting means for attaching and detaching said shields and supporting guides to said base and means on said base adapted to cooperate with said shields for positively locating said shields and supporting guides in a predetermined position against the inner face of said base.

8. The combination with a circular cage body, a circular base portion having a connecting overhang portion and a slot therein, of a tray adapted to be removably entered into said base portion through said slot, said tray having paralleling straight side edges and curved end sections, said tray being of less width than the diameter of said cage, shields adapted to be removably attached to said base portion and to cover the spaces between the side edges of said tray and the wall of the base of said cage, an integral supporting guide at the lower extremity of each shield for guiding and supporting said tray, a bead circumferentially of said base portion, the ends of said shields having notches for engagement with said bead, and means for removably attaching said shields and supporting guides to the inner face of said base portion and for bringing the ends of the guides in line with the ends of said slot.

9. The combination with a circular cage body, a circular base portion connected therewith having a slot therein, said base portion having a connecting overhang, and a tray adapted to be removably entered into said base portion through said slot, said tray having paralleling straight sides and curved end sections, said tray being of less width than the diameter of said cage, of shields adapted to be removably attached to said base portion and to cover the spaces between the side edges of said tray and the wall of the base of said cage, supporting guides at the lower extremities of said shields for guiding and supporting said tray, the major portion of said shields extending beneath that portion of said overhang directly above said shield, the top edges of said shields abutting the underface of said overhang and their ends interlocking with the inner face wall of said base portion, and attaching means carried by said shields and supporting guides and extending across the spaces between the side edges of said tray and the inner wall of the base and adapted to pass through said base, and means adapted to be applied to said attaching means exteriorly of the base for removably locking said shields and supporting guides to said base.

10. The combination with a cage body, a base portion connected therewith having a slot therein, said cage body and base portion being tapered to permit cages of the same size to telescope vertically, and a tray adapted to be removably entered into said base portion through said slot, said tray being of less width than the diameter of said base portion and creating open spaces between the side edges of the tray and the inner wall of said base portion, of shields adapted to cover said open spaces when entered into said base portion and having their ends interlocking with the inner wall of said base, supporting guides integral with the lower extremities of said shields for supporting and guiding said tray, and means extending from said guides and traversing said open spaces for removably attaching said shields and guides within said base portion, whereby when said shields and tray are removed

from the base portion a plurality of cages may be telescoped together the major portion of their height for shipping purposes and the shields and tray reentered into the cages after reaching their shipping destination.

5 11. The combination with a cage body, a base portion connected therewith having a slot therein, and a tray adapted to be removably entered into said base portion through said slot, said tray 10 having straight side edges and curved end sections, said tray being of less width than the diameter of said base portion whereby open spaces will be formed between the side edges of said tray and the wall of the base portion, of shields at the 15 sides of said tray adapted to cover said open spaces and form pockets beneath the shields, supporting guides integral with the lower extremities of said shields for guiding and supporting said tray, means connected to and between the 20 ends of said shields and traversing said pockets for removably attaching said shields to the inner face of said base portion and a bead on said base portion cooperating with parts of said shields for preventing undue tilting action of said shields 25 and guides.

12. The combination with a cage body, a base portion connected therewith and having a slot therein, and a tray adapted to be removably entered into said base portion through said slot, said 30 tray being of less width than the diameter of said base portion whereby open spaces will be formed between the sides of said tray and the

wall of said base portion, of shields at the sides of said tray adapted to cover said open spaces and form pockets beneath the shields, supporting guides integral with the lower extremities of said shields for supporting and guiding said tray, 5 means connected to and between the ends of said shields and traversing said pockets for removably attaching said shields to said base portion whereby said shields may be secured within the base of said cage after said cage body and base 10 portion have been permanently secured together, and means at the ends of said shields adapted to coordinate with the contour of the the inner face of said base portion for alining the supporting guides in a horizontal plane with the slots in said 15 base portion.

13. The combination with a circular cage structure comprising a body portion and a base portion, said base portion having a slot therein, of a tray adapted to be entered through said slot, 20 said tray paralleling straight side edges, shields extending from the straight side edges of said tray to the inner walls of said base portion, means on said shields for supporting said tray, the top edges of said shields being curved to fit 25 the inner curved face of said base, and means for interlocking said shields with the wall of said base portion for preventing undue tilting action of said shields, said shields forming reinforcements for said base portion when mounted there- 30 in.

ADOLPH J. HAVLIS.
